UNITED STATES PATENT OFFICE.

GUSTAV WILLRINGHAUS, OF NEWARK, NEW JERSEY, ASSIGNOR TO THE R. NEUMANN HARDWARE CO., A CORPORATION OF NEW JERSEY.

TRUNK CATCH OR FASTENER.

Application filed November 15, 1921. Serial No. 515,393.

To all whom it may concern:

Be it known that I, GUSTAV WILLRINGHAUS, a citizen of the United States, residing at Newark, in the county of Essex and State of New Jersey, have invented certain new and useful Improvements in Trunk Catches or Fasteners; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in that class of catches or fasteners for use with trunks, suitcases, and the like; and, the present invention has reference, more particularly, to a novel trunk or suitcase catch or fastener provided with a simply constructed and positively acting lever-operated mechanism for bringing the two main members of the fastener or catch, one of which is secured to the body of the trunk or other container, and the other one of which is secured to the lid of the trunk or other container, firmly and securely into their locked relation, or for readily releasing the engaged elements of the catch or fastener-mechanism, when it is desired to raise the lid.

The present invention, therefore, has for its principal object to provide a novel and simply constructed, as well as a quickly and readily operated catch or fastener-mechanism for attachment to and used with the bodies and lids of trunks, suitcases, and other containers, and at the same time providing a strong and an efficiently operating means for bringing and retaining the usual holding or retaining loop in a positively fixed closing relation, so as to guard against any accidental separation of the closed members, and against any accidental opening of the lid when shut down upon the body of the trunk, or the like.

Other objects of the present invention not at this time more particularly enumerated, will be clearly understood from the following detailed description of the present invention.

With the various objects of the present invention in view, the said invention consists, primarily, in the novel catch or fas-

tener for trunks, suitcases, and other containers; and, the said invention consists, furthermore, in the novel arrangements and combinations of the several devices and parts, all of which will be more fully described in the following specification, and then finally embodied in the clauses of the claims, which are appended to and which form an essential part of the said specification.

The invention is clearly illustrated in the accompanying drawings, in which:—

Figure 1 is a front elevation of a trunk or suitcase catch or fastener, showing one embodiment of the principles of the present invention, the main parts of the device being represented in their locked relation; and Figure 2 is a similar view of the said catch or fastener, with the main parts of the device shown in their disengaged relation.

Figure 3 is a side elevation of the device represented in said Figure 1; and Figure 4 is a central vertical sectional representation of the same.

Figure 5 is a front elevation of a modified construction of trunk or suitcase catch or fastener embodying the principles of the present invention, said view showing the main actuating parts of the mechanism in their engaged positions.

Similar characters of reference are employed in all of the said above described views, to indicate corresponding parts.

Referring now to the several figures of the drawings, the reference-characters 1 and 2 indicate the respective main body-members of a trunk-catch or fastener, which members may be of any desired marginal configuration, the member 1 being provided with a series of suitably disposed nail-receiving holes 3 for attachment of said member to the body of a trunk, suitcase, or other container, and the member 2 being likewise provided with a series of nail-receiving holes, as 4, for its attachment to the lid or cover of the said body, in the manner usual with such catches or fasteners for trunks, suitcases, and the like.

As shown, the main body-member 1 has suitably disposed and secured upon its outer face a suitably constructed shell or enlargement, as 5, which is preferably hollow and is open at its upper end-portion 6, for the reception of a guide-lug or projection 7, extending in a downward direction from the lower marginal edge of the said body-mem-

- ber 2, substantially as shown in Figures 1, 2 and 4 of the drawings. Pivotedly connected with the sides 8 of the said shell or enlargement 5, by means of its end-members 10 is a wire receiving or retaining loop 9 formed with a connecting member 11, which is usually made arc-shaped, as shown, and the purpose of which will presently be more fully set forth.
- 10 Suitably secured in the proper position to the body-member 2 is a forwardly projecting pivot-pin or stud 12 upon which is rotatably mounted the hub or disc-shaped portion 14 of a releasing arm or lever 13, provided at its free end-portion with a finger-piece, as 15, for rotating the same from its engaging and retaining position shown in Figure 1, to its disengaged position represented in Figure 2 of the drawings. Upon 15 a portion of its marginal edge, the hub or disc-shaped portion 14 of the arm or lever is provided with a loop-receiving and retaining element 16, preferably in the form of a forwardly extending and arc-shaped hook-like member, adapted, when the arm is moved into either of the positions indicated in said Figures 1 and 2, to engage the connecting member 11 of the securing or retaining loop 9, so as to maintain the locked 20 relation of the two body-members 1 and 2, or to be disengaged from said member 11, when it is desired to raise the lid or cover 25 of the trunk, or the like.
- To prevent scratching or marring of the 30 face of the body-member 2, when the arm or lever 13 is rotated in either direction, the face of said member 2 is preferably provided with an arc-shaped rib or projection, as 17, the ends of which are tapered, as at 35 18 and 19, and near which the said body-member 2 is provided with suitably formed teat-receiving depressions 20 and 21, into either of which a teat or projection 22 extending rearwardly from the said arm or lever 13 is sprung, so as to limit the rotary 40 movement of said arm or lever, in either direction, and to hold the same in its loop-engaging or disengaged position, as will be clearly evident.
- 45 In the modified construction of trunk-catch or fastener shown in Figure 5 of the drawings, the reference-characters 23 and 24 indicate the two main body-members of the same, the member 23 being shown 50 with the nail-receiving holes or perforations 25, and the member 24 with the nail-receiving holes or perforations 26. In this construction, the body-member 24 is provided upon its outer face with a forwardly 55 projecting shell or enlargement 27 and a marginal guide-lug or tongue 28, adapted to enter the upper open end-portion of a receiving shell or enlargement 29 extending forwardly from the front face of the body-member 23, substantially as shown. Piv- 60 otally connected with the sides 30 of the shell or enlargement 27, are the end-members 32 of a wire securing or retaining loop 31, formed with a connecting member 33, which is also usually made arc-shaped, as 65 shown.
- Suitably secured in the proper position to the body-member 23 is a forwardly projecting pivot-pin or stud 34 upon which is rotatably mounted the hub or disc-shaped 70 portion 36 of a releasing arm or lever 35, similar to the arm or lever 13, which is provided at its free end with a fingerpiece, as 37, for rotating the said arm or lever into the positions desired. Upon a portion of 75 the marginal edge of the hub or disc-shaped portion 36 of the said arm or lever 35 is a loop-receiving and retaining element 38, similar to the element 16 of the arm or lever 13, adapted, when the arm or lever 35 is 80 moved in either direction, to engage the connecting member 33 of the securing or retaining loop 31, so as to maintain the locked 85 relation of the two body-members 23 and 24, or to be disengaged from said member 33, 90 when it is desired to raise the lid or cover 95 of the trunk, or the like.
- In order to prevent scratching or marring of the face of the said body-member 23, when the arm or lever 35 is rotated in either 100 direction, the face of said member 23 may also be provided with an arc-shaped rib or projection, as 39, the ends of which are tapered, as at 40, and near which the said body-member 23 is provided with suitably 105 formed teat-receiving depressions 41, into which a teat or projection 42 extending rearwardly from the arm or lever 35 can be sprung, for maintaining the said arm or lever in either of its rotated positions, as 110 will be evident.
- The manner of operating the arm or lever of the catch or fastener and its action with respect to the holding or retaining loop will be clearly understood from an inspection of 115 the several figures of the drawings, and is extremely simple, so that any further description of the same is deemed unnecessary.
- Of course I am aware that some changes 120 may be made in the general arrangements and combinations of the devices and parts, without departing from the scope of the present invention as set forth in the foregoing specification, and as defined in the clauses of the claims which are appended 125 thereto. Hence, I do not limit my present invention to the exact arrangement and combination of the said devices and parts as described in the said specification, nor do I confine myself to the exact details of the 130 construction of the said parts, as illustrated in the accompanying drawings.
- I claim:
1. A catch or fastener for trunks, and the like, comprising a pair of body-members, 135

- one of said members being provided with an 40
enlargement, and the other body-member
being formed with a series of pin-receiving
depressions forming stops, a retaining loop
5 pivotally connected with said enlargement,
a lever pivotally mounted upon the outer
face of said last-mentioned body-member, a
stop-pin extending rearwardly from said
lever, adapted to enter into arresting en- 45
gagement with either of said receiving de-
pressions, and means carried by said lever,
said means being adapted to be moved into
and out of retaining engagement with said
loop, with the respective movements of said 50
lever.
2. A catch or fastener for trunks, and the
like, comprising a pair of body-members,
one of said members being provided with an
enlargement, and the other body-member 55
20 being formed with a series of pin-receiving
depressions forming stops, a retaining loop
pivotally connected with said enlargement,
a lever pivotally mounted upon the outer
face of said last-mentioned body-member, a
25 stop-pin extending rearwardly from said
lever adapted to enter into arresting engage-
ment with either of said receiving de-
pressions, and a hook-shaped marginal loop-
receiving and retaining means extending
30 from said lever adapted to be rotated into
and out of retaining engagement with said
loop, with the respective movements of said
lever. 60
3. A catch or fastener for trunks, and the
like, comprising a pair of body-members,
one of said members being provided with an
enlargement, and the other body-member 65
35 being formed with a forwardly projecting
arc-shaped rib and with a series of pin-
- receiving depressions providing stops, a re-
taining loop pivotally connected with said
enlargement, a lever pivotally mounted
upon the outer face of said last-mentioned
body-member, a stop-pin extending rear- 70
wardly from said lever, adapted to enter
into arresting engagement with either of
said receiving depressions, and means car-
ried by said lever, said means being adapted
to be moved into and out of retaining en-
gagement with said loop, with the respec-
tive movements of said lever.
4. A catch or fastener for trunks, and the
like, comprising a pair of body-members,
one of said members being provided with an
enlargement, and the other body-member be-
ing formed with a forwardly projecting 75
arc-shaped rib and with a series of pin-
receiving depressions providing stops, a re-
taining loop pivotally connected with said
enlargement, a lever pivotally mounted upon
the outer face of said last-mentioned body-
member, a stop-pin extending rearwardly
from said lever, adapted to enter into arrest-
ing engagement with either of said receiving
depressions, and a hook-shaped marginal 80
loop-receiving and retaining means extend-
ing from said lever adapted to be rotated
into and out of retaining engagement with
said loop, with the respective movements of
said lever.

In testimony that I claim the invention
set forth above I have hereunto set my hand
this 14th day of November, 1921.

GUSTAV WILLRINGHAUS.
